By G. W. Gray ~~Att.~~

UNITED STATES PATENT OFFICE.

HARRY A. DOUGLAS, OF BRONSON, MICHIGAN.

CIRCUIT-CONNECTOR.

1,286,961.

Specification of Letters Patent. Patented Dec. 10, 1918.

Application filed April 4, 1917. Serial No. 159,728.

To all whom it may concern:

Be it known that I, HARRY A. DOUGLAS, citizen of the United States, residing at Bronson, in the county of Branch and State 5 of Michigan, have invented a certain new and useful Improvement in Circuit-Connectors, of which the following is a full, clear, concise and exact description.

My invention relates to circuit connectors 10 and to the means for mounting them and is of particular service when employed in assembling lamp casings with incandescent lamps in the manufacture of headlights, taillights, etc., and is also particularly of 15 service in assembling circuit couplers with the lamp casings of headlights. In practising my invention the shell which is employed for holding contact carriers such as the lamp bulb and the plug by which the 20 lamp bulb is included in circuit is provided with projections between which a portion of the lamp casing, reflector, or other mounting is interposed. The portion of the mounting which immediately surrounds the shell 25 is preferably of conical or tapering formation. The shell preferably has an outsetting bead and a tongue between which the aforesaid portion of the mounting is interposed, the bead engaging the adjacent edge of said 30 portion of the mounting while the tongue engages the inner sloping face of said mounting portion that in turn slopes toward the shell. By this construction a rigid assembly of the connector shell and the lamp 35 casing may be effected. In assembling the shell and its mounting the tongue is desirably projected after the bead is positioned in engagement with the shell mounting whereafter the tongue, which initially is flush 40 with the shell, is pressed into firm engagement with the mounting.

I will explain my invention more fully by reference to the accompanying drawings showing preferred embodiments thereof and 45 in which Figure 1 shows the adaptation of the invention to a headlight structure; Fig. 2 shows the adaptation of the invention to a taillight structure; Fig. 3 is a view in sectional elevation illustrating the invention; Fig. 4 is a view on line 4-4 of Fig. 3; Fig. 5 is a sectional view illustrating the assembly of the shell with its mounting, the contact carriers being omitted, this view being taken on line 5-5 of Fig. 6; Fig. 6 is a 55 view on line 6-6 of Fig. 5; Fig. 7 is a perspective view illustrating another form of

mounting; and Fig. 8 is a view, mainly in section, showing the assembly of the mounting with a contact carrying shell.

Like parts are indicated by similar characters of reference throughout the different figures.

The types of lamps shown in Figs. 1 and 2 are well known to those skilled in the art and need not be specifically described. In 60 Fig. 1 the shell 1 is held in assembly with the reflector 1¹ in accordance with my invention. In Fig. 2 the shell 2 is held in connection with the casing 2¹. The connector shell 3 is held in connection with the casing 3¹ of 70 the lamp shown in Fig. 1. In both of these figures the elements 1¹, 2¹, 3¹ each constitute a mounting for a connector shell. As Figs. 1 and 2 are on a small scale the invention will be further specifically described by reference to the remaining figures. 75

Referring first particularly to Figs. 3 and 4 which illustrate the assembly of the shell 1 with its mounting 1¹, the shell 1 carries a plug 6 at one end, this plug being adapted 80 for the reception of the terminal 7 of a circuit conductor that is employed for including the lamp bulb 8 in circuit. The connector shown in Fig. 3 is a single pole connector in which event the plug 6 carries 85 one spring pressed contact 9. The lamp bulb 8 carries bayonet pins 10 that are receivable in bayonet slots 11. The base of this lamp bulb constitutes a contact carrier and has a contact 12 which is engaged by the spring 90 pressed contact 9. The shell includes a bead or projection 13 and tongues 14 which tongues are initially flush with the shell but are pushed outwardly into the sloping position illustrated by means of 95 a tool when the shell is to be assembled with its mounting 1¹, it being noted that said tongue and bead are integrally formed with the shell. The end of the tongue is in abutting engagement with the sloping face of the 100 mounting. The hole in the mounting in which the shell is received is the marginal portion 16 thereof of conical or tapering formation, sloping toward the shell 1, that is interposed between the bead 13 and the 105 tongues 14. In assembling the shell with its mounting the end of the shell having the tongues 14 is passed through the opening in the mounting, the tongues then clearing the mounting as they are initially flush with the 110 shell. After the bead 13 has been positioned against the edge of the marginal portion 16

of the mounting 1¹, the tongues 14 are engaged by a tool and are forced into the sloping positions illustrated in which positions these tongues firmly press upon the inner 5 sloping face of the marginal portion 16 of the mounting to force the edge of this marginal portion into firm engagement with the bead 13. By this arrangement the bead 13 and the tongues 14 have firm gripping engagement with the mounting 1¹ and, when desired, may be rigidly assembled therewith if the pressure applied by the tongues 14 is sufficient.

Figs. 5, 6, 7 and 8 illustrate the assembly 15 of the mounting 3¹ and the shell 3 of Fig. 1 and the formation of the mounting itself is somewhat modified. The parts of Figs. 5, 6, 7 and 8 which are similar to the parts shown in Figs. 3 and 4 are given similar 20 characters of reference, it being stated that the connector of Fig. 8 has two spring pressed contacts 9¹ and two contacts 12¹ upon the carriers for these contacts and that the contact carrier 6¹ carries bayonet pins 6² 25 by which it may be assembled with the shell 3 that has suitable bayonet slots 6³. In Figs. 3 and 4 the tapering or conical portion 16 is annular whereas in the construction of Figs. 5, 6, 7 and 8 the portion 16 is in sections that are separated by the unsloping 30 portions 16¹ of the mounting 3¹ whereby shoulders 16² are formed between which the tongues 14 are disposed. In the event that

the tongues 14 do not engage the mounting 3¹ with sufficient force to prevent the shell 35 from rotating in its mounting the shoulders 16² will prevent such rotation.

Having thus described my invention I claim as new and desire to secure by Letters Patent the following:—

1. A circuit connector including a shell; and contact carriers carried by the shell, said shell having a projection and a tongue integrally formed with and projecting from said shell; in combination with a mounting 45 provided with an opening in which said shell is received, a portion of the mounting immediately adjacent the shell sloping toward the shell and being interposed between said projection and tongue, the projection 50 engaging the adjacent edge of said sloping portion of the mounting while the tongue is angularly disposed with respect to the inner sloping face of said mounting portion with the end of the tongue in abutting engagement with said sloping face.

2. A circuit connector including a shell; and contact carriers carried by the shell, said shell having a projection and a tongue integrally formed with and projecting from 60 said shell; in combination with a mounting interposed between and engaged by said projection and tongue.

In witness whereof I hereunto subscribe my name this 3rd day of March A. D. 1917. 65
HARRY A. DOUGLAS.
